C. P. CARROLL.

DISPLAY STAND.

APPLICATION FILED NOV. 1, 1917.

1,299,677.

Patented Apr. 8, 1919.

THE NORRIS PETERS CO., PHOTO-LITHO, WASHINGTON, D. C.

UNITED STATES PATENT OFFICE.

CORNELIUS P. CARROLL, OF COLUMBIA, LOUISIANA.

DISPLAY-STAND.

1,299,677.

Specification of Letters Patent.

Patented Apr. 8, 1919.

Application filed November 1, 1917. Serial No. 199,649.

To all whom it may concern:

Be it known that I, CORNELIUS P. CARROLL, a citizen of the United States, residing at Columbia, in the parish of Caldwell and 5 State of Louisiana, have invented certain new and useful Improvements in Display-Stands; and I do hereby declare the following to be a full, clear, and exact description of the invention, such as will enable others 10 skilled in the art to which it appertains to make and use the same.

This invention relates to new and useful improvements in display stands and the primary object of the present invention is 15 to provide a stand of this character wherein a plurality of rolls of wire fabric are supported upon a reel, means being provided for accurately measuring the wire as it is unwound from any selected roll.

Another object of the invention is to provide means for locking the reel in any selected position.

A further object of the invention is to provide a reel with a plurality of spring 25 loops adapted to support wire roll casings, each casing being provided with a longitudinal slot through which the wire may be freely extended and attached to and wound upon the core supported immediately above 30 the reel.

A still further object of the invention is to provide the lower part of the display stand with a plurality of brackets adapted to support rolls of wire, any of which may be readily and conveniently substituted for the 35 rolls positioned within the casings of the reel.

With these and other objects in view as will appear as the description proceeds, the 40 invention comprises the various novel features of construction, combination and arrangement of parts as will be fully described hereinafter and afterward specifically claimed.

Referring to the drawings:

Figure 1 represents a perspective view of my novel construction of wire display stand.

Fig. 2 represents an enlarged vertical 50 fragmentary sectional view through the upper side portion of the stand, and

Fig. 3 represents a detail sectional elevation of the measuring device.

In order that the construction and operation 55 of the invention may be readily comprehended by those skilled in the art to

which the invention relates, I have illustrated an approved embodiment thereof in the accompanying drawings and will now proceed to fully describe the same, in connection with said drawings, in which 1 indicates a rectangular base or frame work and supports at its ends standards 2 and 3 connected adjacent their lower ends by a cross bar 4. Braces 5 extend from the cross bar 65 4 downwardly to the sides of the base and have attached thereto suitable brackets 6 to support rolls of wire fabric.

A reel 7 is journaled between the standards 2 and 3 immediately above the cross 70 bar 4 and comprises a shaft 8 rotatably and removably positioned in bearings 9 mounted on the inner faces of the standards. A head 10 is rigidly mounted at each end of the shaft and is provided circumferentially 75 with notches or recesses 11 in each of which is rigidly mounted a spring loop 12. These loops support and frictionally hold casings 13, each of which is provided at one end with a stop flange 14 which engages one 80 of the spring loops to prevent the casing from being shoved through and accidentally disengaged from the loops when arranged in proper position. Each casing is provided with a longitudinal slot 15 through 85 which the wire from the roll positioned within the casing is adapted to be drawn.

One of the heads 10 is provided in its outer face with a circumferential row of sockets 16 which are selectively engaged by 90 the inner end of a latch bolt 17 slidably mounted through the standard 2. The bolt is provided adjacent its inner end with a collar 18 adjustably mounted thereon by a set screw 19. 20 indicates a tubular bracket 95 mounted on the inner face of the standard to receive the collar 18 and an expansion spring 21 positioned around the bolt 17 between the collar and the inner end of the bracket 20. This spring will exert its tension to cause the inner end of the latch bolt to snap into each of the sockets 16 as the reel is rotated to hold the reel in any selected 100 rotated position to permit of the wire being unwound from the roll positioned in the uppermost casing. The outer end of the latch bolt extends through a tubular bearing 22 and is provided with a pin 23 which normally rests within a slot 24 formed longitudinally of the bearing. A handle 25 is 105 connected to the outer end of the latch bolt by which the latter may be withdrawn

110

against the tension of the spring 21 until the pin 23 is out of the slot 24 whereupon the handle may be slidably turned so that the pin will rest against the outer edge of the bearing, thus holding the inner end of the latch bolt out of engagement with the socket 16. This will permit a free rotation of the reel.

26 indicates a core rotatably mounted in the upper ends of the standards, said core being provided at one end with a trunnion 27 removably positioned within a slot 28 in the upper end of the standard 3, and at its other end with a plate 29 having a central socketed boss 30 to receive the non-circular end of a shaft 31 mounted transversely through the standard 2 and in bearings 32 and 33 secured to the opposite faces of the standard. A crank handle 34 is rotatably positioned through a restricted opening 35 in the bearing 33 and is detachably connected to the shaft 31. By this construction the core can be freely rotated by the crank handle to wind the wire from the roll within the tubular casing 13.

The core 26 is provided longitudinally with a V-shaped recess 36 which receives a corresponding wedge section 37, said section being hingedly connected at one longitudinal edge to the core and adapted to be secured at its opposite longitudinal edge to the core by suitable clamping means as indicated by the numeral 38.

When it is desired to remove a desired length of wire from the uppermost roll of the reel, the free end of the wire is engaged within the V-shaped groove of the core and rigidly held through the medium of the wedge section. Then by rotating the crank handle any desired amount of wire may be taken from the wire roll and wound upon the core.

39 indicates a measuring device supported by the upper end of the display stand by which the wire as it is wound upon the core may be accurately measured, said measurement being plainly visible at all time as the wire is being measured. The measuring device is supported by a suitable bracket 40 attached to the standard 3. 41 indicates a supporting arm which is pivotally connected at one end of the bracket 40 as at 42, while its other end is connected to the casing 43 of the measuring device. A friction wheel 44 is journaled within the casing and carries a pin 45 on one face thereof which is adapted to engage the teeth of a wheel 47. The friction wheel 44 is adapted to bear upon the core and be rotated by the rotation of the latter. The friction wheel 44 is adapted to be held against counter rotation by a spring 44^a having one end secured to the casing and the other end bearing against the wheel

and coöperating with ratchet shoulders 44^b on the wheel 44. One of the trunnions 48 of the wheel 44 is provided with a pointer 49 which coöperates with graduations 50 on one side face of the casing 43. One of the trunnions 51 of the wheel 47 is also provided with a pointer 52 which coöperates with 65 graduations 53. The graduations 50 indicate inches while the graduations 53 indicate feet, and it is to be understood that each revolution of the wheel 44 will cause the wheel 47 to move one notch by virtue of the 70 pin 45 engaging a tooth thereof.

When it is desired to attach the free end of the wire to the core 26, the measuring device may be swung upwardly into an out of the way position against an angular stop 80 54 carried by the bracket 40. After the wire has been attached, the measuring device may again be swung down into position and by virtue of its own weight will firmly rest upon the core and accurately measure the 85 wire as it is wound thereon.

Having described my invention, what I claim as new, is:—

1. A display stand comprising a supporting base, standards at opposite sides thereof, 90 a wire roll supporting reel journaled upon and between said standards and embodying opposite spaced head plates, spring loops attached circumferentially to each head plate at spaced intervals and adjacent said standards, a wire roll casing adapted to pass through each aligned pair of said loops and provided with a lateral flange at one end to engage one of the loops, and a winding core wound upon said standards in alignment 100 with the axis of said reel.

2. A display stand comprising a supporting base, standards at opposite sides thereof, a wire roll supporting reel journaled upon and between said standards and embodying 105 opposite spaced head plates, spring loops attached circumferentially to each head plate at spaced intervals and adjacent said standards, a wire roll casing adapted to pass through each aligned pair of said loops and 110 provided with a lateral flange at one end to engage one of the loops, a winding core provided at one end with a trunnion to seat in a slot at the top of one standard and at the opposite end with a socketed plate, and a 115 winding shaft rotatably mounted at the upper end of one standard and provided at its inner end with means to fit the socket in said plate.

In testimony whereof I have signed my 120 name to this specification in the presence of two subscribing witnesses,

CORNELIUS P. CARROLL.
